UNITED STATES PATENT OFFICE.

ROLON W. FOSTER, OF NEEDHAM, MASSACHUSETTS, ASSIGNOR TO ESSEX MANUFACTURING COMPANY, OF KITTERY, MAINE, AND LYNN, MASSACHUSETTS, A CORPORATION OF MAINE.

FOOT-CUSHION.

1,013,992.

Specification of Letters Patent.

Patented Jan. 9, 1912.

Application filed January 10, 1910. Serial No. 537,212.

To all whom it may concern:

Be it known that I, ROLON W. FOSTER, citizen of the United States, residing at Needham, in the county of Norfolk and 5 State of Massachusetts, have invented certain new and useful Improvements in Foot-Cushions; and I do hereby declare the following to be a full, clear, and exact description of the invention, such as will enable 10 others skilled in the art to which it appertains to make and use the same.

My invention relates to cushions and supports for the feet and more particularly to a cushion or support to be worn inside of the 15 boot or shoe and adapted to conform to the bottom of the foot of the wearer to produce a yielding and cushioning support for the foot and to yieldingly support the arch of the foot and to prevent and correct the tendency of the wearer to tread over either to 20 the outside or the inside.

Arch supporting devices as heretofore made are constructed in a rigid manner of comparatively stiff and heavy sole leather 25 and metallic stiffening plates, and while they will support the bones of the arch of the human foot, they are, because of their stiff and unyielding nature, extremely uncomfortable to the wearer, and in many cases 30 aggravate instead of correct the trouble which they are designed to correct and cause considerable pain to the wearer, to such an extent that when first used it is often necessary for the wearer to "break them in" as 35 it were, by using them a short time and removing them to rest the feet.

The object of my invention is to produce a foot cushion and arch supporter so constructed and of such materials that it will 40 afford a yielding comforting and self-conforming support and brace to the foot.

To the above ends my invention consists of the improved foot cushion and arch support which will be hereinafter described and 45 claimed.

My invention is illustrated in the accompanying drawing in which—

Figure 1 shows a perspective view of one 50 form of my invention. Fig. 2 shows a transverse sectional view through the flanged portion of the device. Fig. 3 shows a longitudinal sectional view of the device shown in Fig. 1. Fig. 4 shows a modified form of the device. Fig. 5 shows a transverse sectional view through the heel cushion. 55

Similar reference characters will be employed throughout the specification and drawing to designate corresponding parts.

My invention comprises a cushioning support a which in general outline conforms to the shape of the rear portion of a shoe sole and having at one end a heel pad a^1 and cut off at its opposite end a^2 approximately at the forward end of the shank or adjacent to the beginning of the ball of the sole. 60

Between the heel pad a^1 and the forward edge a^2 , the cushioning support is narrowed or contracted as at a^3 , and the narrowed or contracted portion is bounded upon either side by the upwardly and outwardly curved 70 flanges a^6 and a^7 , the flange a^6 extending along the inner side of the arch portion of the foot when the device is in use and the flange a^7 along the outer side of the foot.

As shown in the drawing, these flanges a^6 75 and a^7 are of different heights, the flange a^6 being considerably higher than the flange a^7 , and between the flanges the support is curved transversely as shown at a^8 in Fig. 2. The flanges a^6 and a^7 are curved at their upper 80 edges as shown at a^9 , and these curved edges gradually approach and merge into the surface or body of the cushion at either end.

The device as thus described is constructed of a filling or body consisting of a homogeneous, elastic and cellular material b such as sponge or moss rubber molded to the desired shape, which body or filling is confined between an under covering b^1 and an upper covering b^2 preferably of leather of a sufficient degree of weight and thickness to have imparted thereto by molding the desired shape or configuration, the two coverings b^1 and b^2 being stitched together along their marginal edges as shown at b^8 . 90

In the form shown in Fig. 1, the heel portions of the leather coverings b^1 and b^2 are brought in contact with each other and have the general outline of a heel lift, thus forming a pad for the heel of the foot. 100

In the form shown in Fig. 4 the device is exactly the same as that described, with the exception that the heel pad a^{10} will have a thickened or cushioning filling a^{11} of a character similar to the cushion or filling b hereinbefore described and preferably formed integrally with the cushioning or filling of the fore part, the filling a^{11} being covered by the covering b^2 and the covering b^1 . 105

It will be particularly noted that the under surface of the heel pad a^{10} of the device shown in Fig. 4 will be convexly curved both longitudinally and transversely as indicated by reference characters b^4 and b^5 . See Figs. 5 and 6.

The cellular material b being a yielding and self-conforming member throughout, acts as a multiplicity of small springs directed perpendicular to the surface of the foot against which the said material acts. As the foot cushion and arch supporter conforms in shape to the natural foot and throughout the sides as well as the bottom of the foot, the spring cushion of the elastic cellular material molds the foot into the natural shape and yieldingly supports the sides and arch of the foot. The act of walking causes a compression of the cellular material, thus gently exercising the arch structure causing increased circulation of blood; thus it strengthens the muscles, and ligaments of the arch and promotes a cure, rather than the debilitating effect of a rigid unyielding and nonconforming arch support. This conformation of the under surface of the heel pad a^{10} causes it to fit accurately the depressed heel seat portion of the inner sole of the boot or shoe effectually positioning the foot cushion in the proper position and preventing it from slipping forward beneath the foot of the wearer while in use.

Having described my invention I claim as new and desire to protect by Letters Patent of the United States—

1. A foot cushion or arch support comprising a molded homogeneous elastic cellular body, having at one end a heel seat or

pad and a thick narrowed body portion intermediate its ends, upwardly and outwardly curved flanges extending along said narrowed body portion and merging at either end into said body portion, one of the said flanges being higher than the other and the upper surface of the cushion and the flanges curved from side to side, substantially as described.

2. A foot cushion or arch support comprising a molded homogeneous elastic cellular body, having at one end a heel seat or pad and a thick narrowed body portion intermediate its ends, upwardly and outwardly curved flanges extending along said narrowed body portion and merging at either end into said body portion, one of the said flanges being higher than the other and the upper surface of the cushion and the flanges curved from side to side, the said body portion having an upper and under covering of molded leather stitched together along their edges, substantially as described.

3. A foot cushion or arch support comprising a homogeneous elastic, cellular-body shaped to the natural curves of the foot and having thick and thin portions, said thick portions or greatest mass being intermediate the ends of said support, said elastic cellular-body acting against the foot in lines perpendicular to the contacting surface of the foot and throughout the extent of said cushion and support.

In testimony whereof I affix my signature, in presence of two witnesses.

ROLON W. FOSTER.
